(57) **CLAIM**

The ornamental design for a handheld laser induced breakdown spectroscopy analyzer, as shown and described.

DESCRIPTION

FIG. 1 is a front perspective view of the handheld laser induced breakdown spectroscopy analyzer of this invention; FIG. 2 is a view of the left side of the handheld laser induced breakdown spectroscopy analyzer of this invention; FIG. 3 is a view of the right side of the handheld laser induced breakdown spectroscopy analyzer of this invention; FIG. 4 is a front view of the handheld laser induced breakdown spectroscopy analyzer of this invention; FIG. 5 is a rear view of the handheld laser induced breakdown spectroscopy analyzer of this invention; FIG. 6 is a top view of the handheld laser induced breakdown spectroscopy analyzer of this invention; and, FIG. 7 is a bottom view of the handheld laser induced breakdown spectroscopy analyzer of this invention. The dashed lines are for illustrative purposes and form no part of the claimed design.
